UNITED STATES PATENT OFFICE.

GEORGE STILLE, OF STAUNTON, ILLINOIS.

SWITCH-THROWING MECHANISM.

Application filed February 14, 1922. Serial No. 536,522.

To all whom it may concern:

Be it known that I, GEORGE STILLE, a citizen of the United States, residing at Staunton, in the county of Macoupin and 5 State of Illinois, have invented new and useful Improvements in Switch-Throwing Mechanism, of which the following is a specification.

This invention relates to switch throwing 10 mechanism, designed especially for use in shifting cars operating in mines.

One object is to provide a motor car or engine with a controlling element for co-operation with certain track and switch 15 construction hereinafter disclosed, in such manner, that the switch may be thrown, in the event that it is desired to pass thereover in a direction opposite to that in which the switch is set—that is to pass to a siding when 20 the switch is set for the main line, and vice versa.

A further object is to provide a double 25 acting switch throwing device enabling the motorman to make a "running switch," and cause the motor car to proceed along the main line, and the coal cars, uncoupled, to make a siding as in the case of disposing of empty cars at the bottom of a mine shaft.

A further object is to provide, under other 30 conditions a single acting operating element designed for use on switches of tracks leading from the main line into mine entries.

A still further object is to provide for 35 throwing the switch controlling member on the car to neutral position, when it is desired to take the switch in the position in which it has been previously set.

With the foregoing and other objects in view, the invention consists in the novel 40 construction and arrangement of the track and switch mechanism and of the controlling element, as hereinafter described and claimed, it being understood that modifications may be made within the scope of the 45 claims without departing from the spirit of invention.

In the drawings:—

Figure 1 is a plan view, the pivotally mounted throw bar on the car being in a 50 position to throw the switch to permit of the car following the main line.

Figure 2 is a sectional view on the line 2—2 of Figure 1.

Figure 3 is a sectional view on the line 3—3 of Figure 1. 55

Figure 4 is a bottom plan view of the car, parts being broken away and in section.

Figure 5 is a side elevation of the car, with the front portion thereof in section.

Figure 6 is a transverse sectional view 60 through the front portion of the car.

Figure 7 is a plan view of a track construction, illustrating a slight modification.

A motor car, of the type used for the purpose specified, is shown conventionally, and 65 is designated 10. The principal element of the controlling mechanism carried by the car or engine, is the pivotally mounted bar 12, the pivotal point 13 being intermediate of the forward and rear trucks. This bar is of 70 gradually reduced cross section from the central portion toward the opposite ends, and the extreme ends are beveled to produce blade like members.

The forward platform of the car is designated 16 and the flooring is provided with a slot 17 through which a vertically extending bar 18 projects. This bar is rigidly mounted at 19 in the operating or controlling bar and serves as a handle or lever for 75 throwing that bar. In order to retain the handle in neutral position, I provide a hinged and notched element 20, mounted as shown and adapted to be swung into position for engaging the handle and retaining 80 the operating bar in line with the main longitudinal axis of the motor car. In order to retain the bar 12 in an operative position, in either direction in which it may be thrown, I provide a compression spring 23 which en-

circles a rod 24 carrying an apertured element 25 on one end, this element serving to connect the bar with the motorman's operating handle. The opposite end of the compression spring bears against the apertured element 25, and the bar enters the apertures in this element, and is freely movable therein. When the motorman's operating handle is thrown to either side, and the corresponding end of bar 12 is similarly thrown to cause the set bar 12 to assume a position diagonally of the car bottom, the spring is compressed as the central point is passed, and then relaxes to retain the element in the 95 desired position, that in operative position.

Proceeding to the description of the track 100

mechanism and switch, a portion of the main line is designated 30, and a portion of a siding is shown at 31. The switch points are designated 32 and 33. A bar 34 extends transversely of the switch points and is pivotally secured thereto at the points 35 and 36, by means of bolts passing through the flanges 37 and 38.

A long switch bar 40 is pivotally mounted 10 at 41 on a stationary element, such as a cross tie, this bar 40 being provided with a downwardly extending pin or the like 42 engaging a notch 43 in the transverse bar connecting the switch points. Pivotally connected 15 with one end of bar 40 is a rod 45, one end of which passes through apertured guiding element 46 rigidly secured to a tie, the rod just referred to being encircled by a compression spring 47, the spring bearing 20 against the apertured element and against the enlarged portion of the rod on which the spring is mounted. This construction just referred to is similar to that employed in connection with the long pivoted bar carried 25 by the bottom of the car, but in this instance serves to retain bar 40 in either position in which it may be thrown. In opposite ends of bar 40 are the pins 48 and 49, these pins being engaged by bar 12 on the 30 car bottom, in the event that that bar is thrown out of neutral position, that is thrown to operative position in either direction. It will be noted that bar 40 is pivoted at a point near the switch point, but 35 slightly spaced therefrom, and that one of the pins carried by the bar 40 is in a position between one of the rails of the siding and one of the rails of the main track. The bar 12, if in neutral position, passes between pins 48 and 49, neither one being engaged, so that the switch is not thrown.

A transverse bar 52 is provided with a cut-away portion 53 having abrupt walls 54 and 55 against which the element 56 on the lower 45 side of bar 40 contact when this end of bar 40 is thrown to either position.

If the switch is set for the siding, and the motorman's switch controlling handle is thrown toward the right side of the car, the pin 48 on bar 40 first engaged by operating bar 12 will be in the position shown in Figure 1. Owing to the diagonal position of bar 12, the engagement between this element and the pin just referred will throw bar 40 and throw the switch points to the opposite position so that the motor car may take the main line, the coal or ore car being then uncoupled,—and the motor car proceeding, bar 12 will come into engagement with the pin on the opposite end of bar 40 and will reverse the position of the switch points, so that the coal cars will take the siding, as in the case of disposing of empty cars at the bottom of a mine shaft.

Upon reversing the motor car but not re-

versing the switch controlling handle, the pin on bar 40, last referred to is first engaged and the position of the switch point is reversed, so that the car may move in the opposite direction on the main line, to any point beyond the siding. The pin at the opposite end of bar 40 is next engaged, and the switch points are restored to original position, the switch being set for the siding.

If the switch is set for the main line, and the car is moving toward the left, as shown in the drawing, is to take the siding, the motorman's handle 18 is thrown to the left, and the pin 48 on bar 40 first engaged, throws this bar and the switch points to opposite position, the car proceeds towards the siding, and passing the other pin 49 on bar 40 engages that pin and the switch is restored, leaving the main line cleared.

The short switch bar 50 is used on switches 85 leading into the mine entries from the main track. This bar 50 carries a single pin 50', and the switch is thrown once, and is not restored.

Having thus described my invention, I 90 claim:

1. The combination with a plurality of switch points and elements connecting the same, of a bar pivotally mounted between the switch points and acting to throw said connecting element and switch points, engaging devices carried by the bar, a second bar pivoted to the bar first named, a guiding element through which the free end of the second bar passes, and a spring bearing 95 against the guiding element and acting to retain the bar first named at an angle with reference to the second bar, and retaining the switch points in either position in which they are thrown.

2. The combination with a bar controlling a track switch and engaging devices carried by the bar, of car carried means cooperating with said engaging devices, successively, for moving the switch points toward and away from adjacent rails of a track, said car carried means including a bar pivoted for movement in a horizontal plane.

3. The combination with a bar controlling a track switch and engaging devices carried by the bar, of car carried means cooperating with said engaging devices, successively, for moving the switch points toward and away from adjacent rails of a track, said car carried means including a bar pivoted for movement in a horizontal plane, and means for retaining the bar last named in a plurality of operative positions.

4. The combination with a bar controlling a track switch and engaging devices carried by the bar, of car carried means cooperating with said engaging devices, successively, for moving the switch points toward and away from adjacent rails of a track, said car car-

ried means including a bar pivoted for movement in a horizontal plane, means for retaining the bar last named in neutral position, and means for retaining this bar in 5 a plurality of operative positions.

5. The combination with a bar controlling a track switch and engaging devices carried by the bar, of car carried means cooperating with said engaging devices, successively, for 10 moving the switch points toward and away from adjacent rails of a track, and means for retaining the bar in a plurality of operative positions.

6. The combination with a bar controlling 15 a track switch and engaging devices carried by the bar, of car carried means cooperating with said engaging devices, successively, for

moving the switch points toward and away from adjacent rails of a track, and means including a pivoted element and a spring 20 for retaining the bar in a plurality of operative positions.

7. The combination with a bar controlling a track switch and engaging means carried by the bar, of car carried means cooperating 25 with the engaging means and including a bar movable to position for contacting with the engaging means and movable to neutral position, and a pivoted rod and spring for retaining each bar in the position in which 30 it is thrown.

In testimony whereof I affix my signature.

GEORGE STILLE.
